US00D550160S

(12) **United States Design Patent** (10) **Patent No.:** **US D550,160 S**
Fujimoto (45) **Date of Patent:** **** Sep. 4, 2007**

(54) **CONNECTOR**

(75) Inventor: **Masaki Fujimoto**, Tsu (JP)

(73) Assignee: **Matsushita Electric Works, Ltd.**,
Osaka (JP)

(**) Term: **14 Years**

(21) Appl. No.: **29/260,946**

(22) Filed: **Jun. 5, 2006**

(30) **Foreign Application Priority Data**

Dec. 5, 2005 (JP) 2005-035785

(51) **LOC (8) Cl.** **13-03**

(52) **U.S. Cl.** **D13/147**

(58) **Field of Classification Search** D13/123,
D13/133, 146-147, 154, 184, 199; 439/79,
439/108, 278, 374, 377, 660, 607-610, 680,
439/682, 883, 891, 894

See application file for complete search history.

(57) **CLAIM**

The ornamental design for a connector, as shown and
described.

DESCRIPTION

FIG. 1 is a perspective view of a connector, showing my new
design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a cross-sectional view thereof, taken along line
8—8 as shown in FIG. 2.

1 Claim, 4 Drawing Sheets
